UNITED STATES PATENT OFFICE.

EBENEZER A. W. JEFFERIES, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GAS-PRODUCER.

1,152,514.

Specification of Letters Patent. Patented Sept. 7, 1915.

Application filed January 20, 1911. Serial No. 603,642.

To all whom it may concern:

Be it known that I, EBENEZER A. W. JEFFERIES, a citizen of the United States, residing at Worcester, in the county of Worcester, and Commonwealth of Massachusetts, have invented a new and useful Improvement in Gas-Producers, of which the following is a specification, accompanied by drawings forming a part of the same.

The objects of my improvement are to secure a more uniform distribution of coal through the chamber; to level the upper surface of the fuel mass and prevent the coalescing or caking of the fuel; to prevent the formation of "pipes" or flues due to the unequal combustion of coal, and to accomplish the more perfect disintegration of the coal during the process of combustion. I attain these objects by the mechanism illustrated in the accompanying drawings, in which—

Figure 1 is a side elevation of a gas producer with the lower portion, from immediately above the upper line of fuel, shown in vertical central section. Fig. 2 is a horizontal section on a line approximately level with the line of the poker.

Similar reference characters refer to similar parts in the different figures.

Referring to the drawings, the gas producer chamber 1 with its upper portion inclosed within walls of a suitable refractory material, is supported upon posts 2 and comprises a lower water cooled section 3 extending downward into a rotatable ash pan 4 which is supported upon friction rolls 5, and which is rotated by any preferred means of rotation, not shown. A dome 6 with extending arms 7 is supported upon and rotated by the ash pan and provides a passage of entrance for the necessary blast of air and steam which is conducted into the bottom of the gas producer chamber 1 through the arms 7. The rotation of the dome 6 and arms 7 imparts a rotative movement to the mass of fuel in the gas producer chamber above them.

The above described construction is similar to that in use in gas producers at the present time and forms no part of my present invention.

Mounted upon the extended shaft 8 of one of the friction rolls 5 is a sprocket wheel 9, connected by a chain 10 with a second

sprocket wheel 11, which is mounted upon a hollow shaft 12 journaled in a bearing 13 on the top of one of the posts 2. Extending through the chamber 1 just below the line of the fuel is a rotatable water pipe forming a water cooled poker 14, journaled in hollow water cooled bearings 15 and 16 held in alinement in the walls of the chamber 1. One side of the poker 14 is connected with the hollow shaft 12 which is driven by the sprocket wheel 9 and through which the poker 14 is supplied with water. The opposite end of the poker 14 is connected with a hollow shaft 17 journaled in a bearing 18 supported upon the top of the lower water cooled section 3 of the gas producer chamber. The hollow shafts 12 and 17 communicate with the hollow poker 14 and with the pipes 19 and 20 connected with stationary hollow caps 21 and 22 inclosing the ends of the shafts 12 and 17 form a water circulatory system through the poker 14.

The poker 14 is crank shaped as it passes through the chamber 1 between the hollow bearings 15 and 16, and extends obliquely downward from the bearing 15 almost entirely across the chamber where the slant of poker 14 is sharply reversed at 23 extending upward until the end of the poker 14 is in alinement with the bearing 16. It is obvious that the rotation of the poker will cause a change in position of the angle at 23, and the inclined section of the poker revolving it around an axis coincident with the axes of the bearings 15 and 16. The slant of the poker 14 is so arranged in angular extent that when the angle 23 is in its highest position it will be preferably above the mass of fuel, as shown by the dotted lines 24 in Fig. 1. This revolution of the poker 14 is designed to accomplish the breaking up of the upper portion of fuel as it extends through the top of the fuel bed and is in contact with the coal when first introduced into the gas producer. The mass of fuel is carried against the revolving poker 14 by the rotation of the fuel due to the ash pan 100 and mechanism connected therewith as above described, and the revolution of the poker 14 is arranged to correspond with, and accompany in direction, the rotation of the fuel when the poker is passing through 105 the fuel mass. This correspondence in di-

rection is shown by the arrows 25 and 26, Fig. 2, which shows the direction of the fuel and the poker respectively.

The slant of the poker 14 and the angle 5 at 23 is designed when passing through the upper part of its revolution to level the upper surface of the fuel and when in the lower portion of its path to agitate the fuel, to a greater depth. The greatest agitation 10 of the fuel will occur where the poker is buried deepest, or at the section 23 and as the fuel mass is rotated it will become uniformly subjected to the agitating action of the poker. The bearings 15 and 16 for the 15 revolving poker, as shown in Fig. 2, are provided with a water chamber 27 supplied with a water current through the pipes 28 and 29, thereby protecting the bearings 15 and 16 from excess of heat.

20 I claim—

- 20 1. In a gas producer, the combination with a wall inclosing a heating chamber, a rotatable ash pan below said chamber and arranged to support the fuel in said chamber, and means for imparting a rotative movement to the fuel in said chamber, of a rotatable water cooled poker extending through said chamber, and means for rotating said poker.
- 25 2. In a gas producer, the combination with a stationary wall inclosing a heating chamber, a rotatable ash pan spaced below said chamber and arranged to support the fuel in said chamber, and means for rotating said ash pan, of aligned bearings in opposite sides of said wall, a rotatable water cooled

poker journaled in said bearings and extending through said chamber, and means for rotating said poker.

3. In a gas producer, the combination 40 with a wall inclosing a heating chamber, a rotatable ash pan spaced below said chamber and arranged to support the fuel in said chamber, and means for rotating said ash pan, of opposite bearings in said wall with 45 their axes in alinement, a rotatable bent water cooled poker journaled in said bearings, and means for revolving said poker.

4. In a gas producer, the combination 50 with a wall inclosing a heating chamber, a rotatable ash pan spaced below said chamber and arranged to support the fuel in said chamber, and means for rotating said ash pan, of aligned opposite bearings in said wall, 55 a water cooled poker journaled in said bearings and passing through said chamber in an irregular path between said bearings, and means for revolving said poker about an axis coincident with the axis of said bearings.

5. In a gas producer, the combination 60 with a heating chamber for the fuel, a rotating ash support, means for transmitting the rotation of said ash support to the fuel in said chamber, a cranked member extending transversely of said chamber, and means 65 for rotating said member.

Dated this 18th day of January, 1911.
EBENEZER A. W. JEFFERIES.
